UNITED STATES PATENT OFFICE.

HOMER R. STEVENSON, OF SALEM, ILLINOIS.

CORN-HARVESTER.

SPECIFICATION forming part of Letters Patent No. 517,899, dated April 10, 1894.

Application filed August 19, 1893. Serial No. 483,552. (No model.)

To all whom it may concern:

Be it known that I, HOMER R. STEVENSON, a citizen of the United States, residing at Salem, in the county of Marion, State of Illinois, have invented a certain new and useful Improvement in Corn-Harvesters, of which the following is a full, clear, and exact description, reference being had to the accompanying drawings, forming part of this specification, wherein—

Figure 1 is a plan-view. Fig. 2 is a side elevation. Fig. 3 is an end view. Fig. 4 is a detail plan-view of the cutting blade. Fig. 5 is a similar view, showing the knife or blade in its retracted position. Fig. 6 is a sectional view through the same, looking from the front. Fig. 7 is a longitudinal section through the knife. Fig. 8 is a detail view of the advanced gathering arm, showing it in its normal position. Fig. 9 is a similar view, showing the arm in its retracted position. Fig. 10 is a detail view of the arm for taking away the corn from the knives after it is cut. Fig. 11 is a detail view of the bar for discharging the shock; and Fig. 12 is a detail view of one of the slides in the rear section, or platform.

My invention relates to a new and useful improvement in corn-harvesters, and consists, generally stated, in the improved construction of such a machine, in which is combined simplicity, cheapness, and effectiveness of operation.

The object of this invention is to construct a machine of the class described adapted to be drawn by suitable power, so as to embrace the standing corn in the field, and which is adapted to cut two rows at one time. After the corn is cut, it is taken from the knife by suitable means and deposited in a receptacle, awaiting removal by the operator, who takes the same and shocks it on the rear platform of the machine. When the corn is shocked, it is removed by the operator tilting the rear platform, by means under his control, which means embrace, also, a sliding bar, which comes in contact with the shock on the platform and by a rearward movement, forces the same off.

In the drawings, 2 indicates the ground wheels, which are connected by axles 3. These axles support the framing of the machine, which consists of two side rails, in the

rear extremity of which is journaled the rear axle, and whose forward ends extends in advance of the front wheel. Supported by this framing, is a front platform 5, whose front edges are recessed, as at 6^a, as shown in Fig. 1, for the passage of a stalk of corn to the knives 6, which are mounted at the rear of these recesses. Extending upwardly on each side of these recesses are vertical posts or standards 7, the lower ends of which are provided with lateral extensions 8, which extend inwardly or toward each other, and close the passage of the corn-stalk through this recess 6^a. These arms 8 are made yielding by a spring 9, attached to one side of the post 7, and, when the stalk of corn comes in contact with said extremities or arms, the same are forced rearwardly, permitting the stalks to pass into the recess, and, in so doing, the vertical posts 7 are partially rotated. This rotation of the posts swings in arms 10 over the opening 6^a, which grasp or force the stalks of corn, which are without the path of the opening 6^a, into its path, so that the machine will not miss any straggling or bent stalks. After the corn has passed the arms 8, the same are permitted to return to their normal position, across the opening 6^a, by the exertion of the spring 9, and they are thus set ready for another operation. As the machine moves forward, stalks of corn will be received on the knife 6, which will sever the same, and other mechanism, hereinafter described, will take the severed stalk and deposit it in the receptacle ready for removal by the operator.

This knife, as shown in Figs. 4, 5, 6, and 7, is constructed of an angularly-shaped plate, 6, which is formed with a recess in its forward end, into which recess the knife blade, 11, is received. This knife blade runs in guideways mounted beneath the front platform 5 and on each side of the recess 6^a, and is held in a yielding forward position by a spring, or springs, 12, which surround a guide-rod 13, secured to the rear of the recess 6^a. The knife has an extension 14 on its under side, whose lower end is formed with an eye, through which the rod 13 passes. This extension 14 confines the compression spring 12 between it and a collar 15, mounted at the rear end of the rod 13, so that when the stalk comes in contact with the knife-blade 11, the

same is forced rearwardly in its guide-pieces, the spring 12, as the blade is forced farther back, exerting a greater resistance, and should the stalk not be severed by the action of the 5 spring, the blade will continue its backward movement until stopped, and it will then have a rigid relation relative to the frame of the advancing machine and will sever the stalk. The tension of the spring 12 is such that it 10 will always yield before severing the corn stalk, and permit the blade to be forced backward, which backward movement of the blade is utilized in the following manner: Mounted on each side of the blade are two vertical 15 rods 16, upon the upper ends of which are supported swinging arms 17, which arms are adapted to overlap or fold beyond each other when the blade is retracted, and thereby force the stalk of corn against the blade and assist 20 in the severing operation. These arms are caused to swing rearwardly every time the blade is retracted through the medium of a foot 18 on their lower extremities, which engages a recess or notch in the sides of the 25 knife-blade, which causes the rods to partially revolve, as shown in Figs. 4 and 5. After the corn has been severed it is removed from the blades by an arm 19, slidingly mounted in an oscillating post 20, which post is mounted 30 in platform 5 immediately over the front axle. The lower extremity of this post is provided with right-angular extensions 21, with which lugs 22, on the front axle, are adapted to engage alternately, and by such 35 engagement cause the post 20 to be oscillated nearly a quarter of a revolution alternately in opposite directions. By the oscillations of the post, the arms 19 are similarly operated, which is taken advantage of by causing them 40 to be thrust forward and retracted, which will gather in the severed corn from behind the knives. This impellant and retractive movement of the arms 19 is due to the engagement of a lug 23 with a cam-groove 24 in a block 45 25, which is supported by a bracket 26, from the front platform 5. This cam groove is of such shape that it will accommodate the lug 23 in each of its extreme positions, due to the oscillation of the lugs 21, and in one of these 50 extreme positions—the rear—I provide the cam-groove with a gate 27, which will cause the lug 23 to run in the inside cam track, and, by so doing, be retracted or be caused to be withdrawn, to avoid the stalks which might 55 be in advance of the same. After such retraction, the arms are permitted to advance until they are again in position to carry off the severed stalks, at which time they start on their backward movement. The stalks 60 after they have been carried backward by the arms are deposited between the two rails 28, the space between which is closed by a spring gate 29, pivoted to one of the supporting posts for these rails. The rear pivoted platform 30 65 has extending longitudinally its center an inverted V shaped housing 31, the upper edge of which is formed with a slot for the recep-

tion and passage of a bar 32, said slot being curved downward at its front end to permit the bar to rest on the platform and be out of the way, as shown in Fig. 2. This bar has connected to it, about its center, a cord or chain, which passes over a sheave or pulley mounted in the rear end of the inverted V-shaped housing, thence forward over a drum mounted on the rear axle. Mounted on the axle near this drum is a suitable clutch coupling which is operated by a bell crank lever 35, which bell-crank lever is under the control of the lever 36 projecting above the forward end of the platform. The rear end of the platform is recessed at 37, which recesses are in line with the stubble and are closed when the platform is in its normal horizontal position by gates or slides 38, which have extending from their forward ends, rods 39, which are surrounded by compression springs 40. The forward ends of these rods have attached thereto a chain or cord 41, which extends forward and passes over a pulley 42 mounted in the forward end of the platform, which cord is then fastened to the stationary platform. On two sides of this tilting platform are mounted rails, for the convenience of the operator. 95

The operation is as follows: Suitable power being attached to the forward end of the machine, the same is started with the recesses 6^a in alignment with two rows of corn. The first relative change in the position of the parts will be when the arms 8 come in contact with the first cornstalk, at which time said arms will be forced rearwardly, swinging the arms 10 around so as to bring the stalk of corn within the opening 6^a, should 105 said stalk be bent out of line therewith. A further advance movement of the machine will cause the blade 6 to come in contact with the stalk, at which time the blades are forced backward and the arm 17 brought around to hold the stalk against the action of the blade. After the stalk has been severed, it is then taken up by the arms 19 and carried back into the receptacle, which is closed by the spring gate 29. These parts, of course, will 115 again assume their normal position after this actuation, by their respective springs, &c. When the corn has reached this stage, the operator takes the same and begins the operation of shocking it on the tilting platform. 120 When the shock is complete and it is desired to dump the same, a latch or bolt *y*, see Fig. 2 and dotted lines Fig. 1, which is of any suitable construction, is withdrawn through the medium of a string passing through the platform, within easy reach of the operator, which will free the forward end of the tilting platform, and by reason of the rear axles being placed in advance of the center of this platform and upon which axles the platform is 125 pivoted, the same will be tilted backward, as shown in Fig. 2. When the platform is so tilted, the cords 41, running over the pulleys 42, will cause the gates 38 to be forced for- 13

ward against the action of springs 40 and uncover the openings 37, which will permit the stubble to pass therethrough and allow the rear end to approach the ground more closely.

5 the operator then, through the lever 36, throws the clutch into contact with its drum, which will wind the cord 34 thereupon and cause the bar 32 to be carried backward and force the shock from the platform. After the shock

10 has been so discharged, the clutch is thrown off, the bar 32 replaced to its forward position, as shown in Fig. 2, the platform 30 is caused to assume a horizontal position, being caught by a suitable latch, which horizontal

15 position of the platform permits the gates 38 to again slide outwardly and close the openings 37.

Having thus described my invention, what I claim, and desire to secure by Letters Patent, is—

20 1. In a corn harvester, the combination with a sliding blade, of springs for holding said blade against the stalk of corn to be cut, rods mounted on each side of said blade, foot-like

25 projections on said rods which engage with recesses in said blades to operate the rods when the blades are retracted, and arms mounted on the rods which are adapted to swing around when the rods are partially rotated by the engagement of their feet with the blades, substantially as described.

2. In a corn harvester, the combination with the front platform, of a receptacle for receiving the severed stalks from the blade, a rod

30 35 provided with right-angular projections on its lower end, projections on the axle for engaging and oscillating said rod through the medium of its right-angular projections, sliding arms 19 mounted in said rod, and a cam for

40 guiding said arms, substantially as described.

3. In a corn harvester, the combination with the front platform, and a cutting apparatus carried thereby, of a pivoted rear platform, formed with recesses in its rear end, in line

45 with the cutting apparatus, gates for closing said recesses, a cord attached to said gates

and having its other end attached to the front platform, and a pulley, mounted on the lower front edge of the pivoted platform over which said cord runs, substantially as described. 50

4. In a corn harvester, the combination with a front platform and a cutting apparatus which is carried thereby, of a tilting platform located in the rear of the front platform and provided with recesses in its rear which are 55 in line with the cutting apparatus, and spring-closed gates for closing said recesses, which gates are operated to unclose said recesses when the rear platform is tilted, substantially as described. 60

5. In a corn harvester, the combination with the front platform and a cutting apparatus carried thereby, of a tilting platform, which is mounted in the rear of the front platform on the rear axle, a drum mounted on said 65 axle, a clutch mechanism mounted in juxtaposition to the drum, a bar slidably mounted on the platform, and a cord or chain which is wound upon the drum and has its other end connected to the bar, substantially as de- 70 scribed.

6. In a corn harvester, the combination with the front platform and a cutting apparatus which is carried thereby, of a tilting platform pivotally mounted on the rear axle, an inverted V shaped housing extending longitudinally the length of said platform, a bar slidably mounted in a slot in said inverted V-shaped housing, a pulley mounted in the rear of the housing, a drum mounted on the 80 rear axle, a cord which is connected to said bar and passing over the pulley in the rear of the housing is wound upon the drum, and a clutch mechanism for said drum, substantially as described. 85

In testimony whereof I hereunto affix my signature, in presence of two witnesses, this 15th day of August, 1893.

HOMER R. STEVENSON.
